UNITED STATES PATENT OFFICE.

WILLIAM L. BLAIR, OF DENVER, COLORADO.

READING DESK.

Application filed January 19, 1922. Serial No. 530,406.

To all whom it may concern:

Be it known that I, WILLIAM L. BLAIR, a citizen of the United States, residing at Denver, in the county of Denver and State of Colorado, have invented certain new and useful Improvements in Reading Desks, of which the following is a specification.

This invention relates to certain new and useful improvements in reading desks and 10 its principal object is to provide a portable device of light and practical construction which is particularly adapted to support a book in a position so that it may be conveniently read and handled by a person seated in a chair or reclining on a bed or lounge.

Another object of the invention is to provide a device of the above described character which is capable of supporting books 20 of different sizes upon the seat of a chair or the surface of a bed without the use of fastening means and which thereby is adapted for ready adjustment to vary the distance of the book from the eyes of the reader.

Another object of my invention is to provide in a reading desk of the type above referred to, a book-support which is adjustable to vary the angle of inclination at which a book is held thereon; a further object is 30 to so construct the book-support that it may be adapted to hold books of different thicknesses in an open condition without integrate adjustment, and still other objects reside in details of construction all of which will be 35 fully disclosed in the course of the following description taken in connection with the accompanying drawings.

In the drawings in the several views of which corresponding parts are similarly 40 designated,

Figure 1 is a perspective representation of a person seated in an easy chair, showing the reading desk of the present invention in its operative position;

Figure 2, a perspective view of the reading desk drawn to a larger scale;

Figure 3, a plan view of the device drawn to a still larger scale;

Figure 4, a section taken on the line 4—4, 45 Figure 3; and

Figure 5, a rear elevation of the desk looking in the direction of the arrow A, Figure 3.

Referring more specifically to the drawings, my improved reading desk comprises a book-rest which in its preferred form, is

composed of a back-board 5 and a trough-like supporting member 6 at the lower edge thereof.

The back-board may be made of wood or 60 metal in any suitable size and form and the supporting member is preferably composed of thin pliable metal so that it may be readily bent by finger pressure to conform with the thickness of the book supported between 65 its sides.

The longitudinal edge of the supporting member is rolled as at 7, to provide a straight-edged ridge which re-inforces the structure and which may contact with the 70 leaves of a book without a chance of accidental injury.

The back-board is mounted in a slanting position upon a supporting frame 8, the distinctive feature of which resides in a 75 pair of substantially parallel elongated feet 9 which project forwardly of the book-rest to the greater part of their longitudinal extent. The frame as shown in the drawings, is for simplicity and lightness of construction, made of a single piece of wire, but I desire it understood that it may be constructed of different material and in a different manner within the spirit of my invention, as defined in the hereunto appended 80 claims.

The elongated feet 9 made by doubling the wire in U-shaped form, are connected at their rear ends beneath the back-board by cross pieces 10 and 11 which extend loosely 90 through clevises 15 fastened at the underside of the board for their pivotal connection therewith.

The feet are weighted at their forward ends by pieces of metal 12 placed between 95 the spaced members of the doubled wire and they may be provided with sleeves made of rubber, felt or other soft material as shown at 13 and 14 in Figure 4, to prevent injury to the parts of an article of furniture 100 with which the reading desk engages.

The bottom-members of the feet may be longitudinally curved, as shown in Figure 4, to fit a cushion or other rounded surface on which the device is supported, and the inherent resiliency of the metal of which the supporting frame is made, permits of its being deformed to vary the angle of inclination of the book-rest, as indicated in broken lines in the same figure of the drawings. 110

In the use of my invention, the reading desk is placed on a chair or bed so as to

straddle the lap or other part of the body of a person occupying the same in a sitting or reclining position. The forwardly projecting feet of the supporting frame permit of the book-rest being brought to within reading distance from the eyes of the user and they provide conjointly a firm and stable support for the device and a book placed thereon, upon the seat of a chair or 10 the surface of a bed or couch, as the case may be.

The weights at the forward ends of the feet over-balance the back-board and the book even though the device is placed partially beyond the front edge of a chair-seat or other support, and the adjustability of the board allows of its being placed at different angles of inclination, as hereinbefore described.

20 The desk while holding a book in a convenient position for reading, gives to the user perfect freedom to change the position of the legs or other parts of the body and it permits of the hands being employed in 25 different occupations, as for example, sewing or knitting.

My invention is furthermore of particular value to convalescent invalids whose strength is not sufficient to hold a book in an elevated 30 position for any length of time.

The pliable supporting member at the lower edge of the back-board may be made integral therewith or it may be made of a separate piece of metal and fastened by 35 screws, rivets, or other suitable means.

The member provides a strong and rigid support for the book; it is well adapted to hold the leaves of the open book in position, and its pliability permits of its being adjusted to books of different thicknesses by 40 mere finger-pressure.

It will be understood, in this connection, that the forward side of the supporting member is sufficiently low to not obstruct the 45 lower lines of the reading matter on the pages of the book and that its rolled edge engages the leaves just enough to hold them in place and not too high to interfere with their being turned by hand without lifting 50 the book to any inconvenient extent.

Having thus described my invention, what I claim and desire to secure by Letters Patent is:

1. A reading desk comprising a frame and 55 a book-rest adjustably supported thereon in a slanting position, said frame including elongated feet which project forwardly for a substantial distance beyond the lower edge of the book-rest whereby to counter-balance 60 a book supported thereon.

2. A reading desk comprising a wire frame including elongated feet and cross

pieces at the rearward ends thereof, and a slanting book rest pivotally connected with said cross pieces, said feet projecting forwardly of the lower edge of said book rest to conjointly support the book rest and a book thereon by loose engagement with a chair seat or other surface at opposite sides of a reader occupying the same, said frame 70 being deformable by its inherent resiliency whereby to admit of the pivoting of the book rest on said cross-pieces to vary the slant thereof.

3. A reading desk comprising a book rest, 75 a frame supporting said rest in a slanting position and including elongated feet which project forwardly for a substantial distance beyond the lower edge thereof whereby to counter-balance a book on said rest, weights 80 carried at the forward ends of said feet to better overbalance the weight of the book rest and a book thereon, the opposite sides of said frame and the feet thereof being spaced apart to conjointly support the desk 85 on a chair seat or other surface at opposite sides of a reader occupying the same.

4. A reading desk as characterized, comprising a frame formed to provide spaced forwardly and horizontally elongated foot 90 portions and angularly disposed portions rising from the rear ends thereof, and a forwardly slanting book-rest pivotally mounted on the upper ends of said angularly disposed portions, said foot portions being extended 95 for a substantial distance beyond the forward edge of said book-rest whereby to counter-balance a book supported thereon.

5. A reading desk as characterized, comprising a frame formed to provide spaced 100 forwardly and horizontally elongated foot portions and angularly disposed portions rising from the rear ends thereof, and a forwardly slanting book-rest pivotally mounted on the upper ends of said angularly disposed 105 portions, said frame being inherently deformable whereby to effect an angular adjustment of said book-rest.

6. A reading desk as characterized, comprising a frame formed of a single length of 110 bendable wire and shaped to provide spaced parallel and horizontally elongated foot portions and vertically disposed portions rising from the rear ends thereof, cross-connections 115 extending between the complemental of the vertically disposed portions, and a slanting book-rest pivotally mounted on said cross-connections, the vertical portions of said frame being inherently deformable whereby 120 to effect a desired angular adjustment to said book-rest.

In testimony whereof I have affixed my signature.

WILLIAM L. BLAIR.
